UNITED STATES PATENT OFFICE

CLINTON L. WALKER, OF PIEDMONT, CALIFORNIA

WATER SCOOP FOR LOCOMOTIVES

Application filed May 15, 1931. Serial No. 537,736.

This invention pertains to railway locomotives and tenders and more particularly to the means for replenishing the supply of water for the boilers when the engine is in motion. By the present practice water may be scooped from long troughs situated alongside the rails or between them, but this practice is confined to level tangents on the line where the water may be contained in level troughs. In a patent issued to J. Wilkes, Number 1,516,258, November 18, 1924 it is disclosed how water might be scooped on an inclined section of a railroad which I will refer to in this application as a grade, by means of a multiplicity of level troughs at successive elevations corresponding to the grade of the track these troughs being connected by guide members for a follower on the scoop, but applicant is not aware this method has ever been put in practice.

It is the object of this invention to provide means for scooping water from a continuous single unit inclined trough on a grade where the water would not remain at the proper level to permit of scooping. It is the present practice on hilly or mountainous sections of the road either to provide a level section where level troughs may be provided or else to have water tanks of the usual types where the engine must stop to receive water. It is perfectly obvious that in the mountainous sections the engines require more water than they do on a similar length of level line as the power required is greater. It is also well known that it is difficult to start a long train on an up grade, and hence it is objectional to have to stop the train to receive water and that it would be a benefit to provide means for scooping water on inclined sections of the line. By the word line, I refer to the railway roadway including the road bed and rails, etc., over which the trains run. By scooping water, I mean the usual method of scooping the water into the water tank of the tender by the use of a scooped pipe, whereby the velocity of the engine forces the water up and through the pipe into the water reservoir.

My invention consists in providing an inclined trough positioned adjacent the track

in the proper position for scooping and to provide a continuous supply of water at the upper end of the trough to maintain a proper amount of water throughout the length of the trough to permit of scooping. This may be accomplished in several different ways: by providing a continuous water supply at the head end of the trough and allowing the water to escape at the lower end, by providing a controlled supply at the upper end, whereby the water supply will be turned on as the train approaches and turned off after the train has passed. This can be accomplished by well-known electrical methods whereby the approaching train closes the operating switch admitting the operating current to the control mechanism which turns on the water. It may be accomplished by providing a reservoir preferably at the upper end of the trough with a valve and automatic or manual control means whereby the water may be turned on when wanted. At the lower end of the trough there would be preferably a sump for the water to flow into after it has passed through the trough and from this sump the water would be pumped back into the reservoir at the head of the trough. This pump could be automatically controlled by well known methods such, for instance, as by a float in the sump or it could be manually controlled or both. The operation of the preferred form would be about as follows:

The approaching train would automatically close the operating switch which opens the valve to admit water from the reservoir to the upper end of the trough. This should be timed so that the water would reach the lower end of the trough by the time the locomotive had reached the lower end of the trough. The water would be scooped in the usual manner and as the train passes out of the switch control portion of the track, the operating valve would close and the water supply would be closed. As the water at the lower end of the sump rose the float, or other means would start the sump pump and the water would be returned to the reservoir at the upper end of the trough.

One form which the invention may take is

exemplified by the accompanying drawings in which:

Fig. 1 is a side elevation of the water tender for locomotive, showing the means for 5 scooping the water, together with the controls for raising the scoop into its running position.

Fig. 2 is a perspective fragmentary view 10 of a section of the track in which the water trough 1 is positioned between the rails 2 on an inclined section of the track and terminates in its lower end in sump 3, having an overflow outlet 4. Water pump 5 driven by motor 7 and controlled by automatic switch 15 8, through wires 9 and 10 connecting the rails of this insulated section of the track, pumps water from sump 3 through suction pipe 19 and outlet pipe 6 into reservoir 16, having an outlet pipe 14, controlled by an 20 automatic valve 13, which is electrically operated by means of wires 11 and 12, connected respectively to rails 2 of this insulated section of the track. 17 is a pipe line for replenishing the water supply in reservoir 25 16. 15 is a pipe line for filling trough 1 in those cases where the continuous supply of water is available.

Fig. 3 is a side elevation illustrating an 30 optional form of trough which is raised to an elevated position along side the inclined track for scooping water from trains which are moving so slowly that they could not scoop water from the position shown in Fig. 2. Excepting for the raised position of the 35 trough of Fig. 3, the system would be the same and the method of using the same as that employed in the system illustrated in Fig. 2.

The operation of the device would be as 40 follows:

As the train approaches the trough 1 the 45 water scoop 20 is lowered into its scooping position. The elevation of the rails and the trough 1 being relatively such as to permit the water to be scooped without interference when scoop 20 is in its lowered position. As soon as the locomotive reaches the insulated section of the track, the contact of the wheels with the rails closes the circuit 50 through the axles and actuates the automatic switch 8, and admits current to motor 7, and thus starts operation of pump 5. Likewise the circuit is also closed for the electrically operated valve 13, and which 55 opens the valve 13 and admits water into the open end of trough 1. The insulated section of the road would have to be of such length as to permit the water from reservoir to 60 reach the lower end of the trough simultaneously or prior to the scooping operation. When the scooping operation is finished and the train passes out of the insulated section to the track, the pump ceases operation and the electrically operated valve closes, and 65 the water remaining in the trough 1 will

drain into the sump. If a continuous supply of water is available it would be only necessary to have a continuous supply of water at the upper end of trough 1 by means of the pipe line, allowing the excess water 70 to escape from the sump through the overflow pipe.

While I have provided for an automatic electrically operated switch for the pump it is obvious that other means of control would 75 do as well, such for instance, as a float valve in the sump whereby the motor and the pump would be in operation whenever the water in the sump was above a determined level.

While I have shown the preferred embodiment of my invention and the preferred application thereof, it is to be understood that various changes may be made in construction of the apparatus, and that the apparatus may be put to uses other than those 80 described without departing from the spirit of the invention as defined in the appended 85 claims.

Having thus described my invention what I claim and desire to secure by Letters Patent is:

1. An inclined water trough having a longitudinal grade parallel to the grade of the adjacent railway track, and so constructed as to permit the flow of running water from its upper to its lower end, and so located with respect to the track as to permit of scooping water from said trough by passing locomotives, and means for supplying running water in said trough when and as required.

2. An inclined water trough having a longitudinal grade parallel to the grade of the adjacent railway track, and so constructed as to permit the flow of running water from its upper to its lower end, and so located with respect to the track as to permit of scooping water from said trough by passing locomotive, and means for supplying water at the upper portion of said inclined trough continuously.

3. An inclined water trough having a longitudinal grade corresponding to the grade of the adjacent railway track and so located with respect thereto as to permit of scooping water from said trough by passing locomotives, and means for supplying water at the upper portion of said inclined trough when required, and means for returning the water from the lower end of said trough to storage facilities at the upper end of the trough.

4. An inclined water trough having a longitudinal grade parallel to the grade of the adjacent railway track and so located with respect thereto as to permit of scooping water from said trough by passing locomotives, and means for supplying water at the upper portion of said inclined trough when required, and means for returning the water from the lower end of said trough to storage facilities at the upper end of the trough, and

means operated by passing trains for controlling said water supply means.

5. An inclined water trough having a longitudinal grade parallel to the grade of the adjacent railway track, and so constructed as to permit the flow of running water from its upper end to its lower end, and elevated above said railway track to a position substantially level with the top of the locomotive tender and in such a position and at such an elevation as to facilitate scooping water from said trough by passing locomotives.

6. An inclined water trough having a longitudinal grade parallel to the grade of the adjacent railway track, and so constructed as to permit the flow of running water from its upper to its lower end, and elevated above said track to a position substantially level with the top of the locomotive tender and in such a position and at such an elevation as to facilitate scooping water from said trough by passing locomotives, and means for supplying water at the upper portion of said inclined trough when required, and means for returning the water from the lower end of said trough to storage facilities at the upper end of the trough.

7. An inclined water trough having a longitudinal grade parallel to the grade of the adjacent railway track, and so constructed as to permit the flow of running water from its upper to its lower end, and elevated above said track to a position substantially level with the top of the locomotive tender and in such a position and at such an elevation as to facilitate scooping water from said trough by passing locomotives, and means for supplying water at the upper portion of said inclined trough when required, and means for returning the water from the lower end of said trough to storage facilities at the upper end of the trough, and means operated by passing trains for controlling said water supply means.
